UNITED STATES PATENT OFFICE.

JAMES BOWERS, OF NEWARK, NEW JERSEY.

DESIGN FOR A CORSET.

SPECIFICATION forming part of Design No. 14,535, dated January 8, 1884.

Application filed October 1, 1883. Term of patent 7 years.

To all whom it may concern:

Be it known that I, JAMES BOWERS, a citizen of the United States, residing at Newark, in the county of Essex and State of New Jersey, 5 have invented a certain new and original Design for Corsets; and I do hereby declare the following to be a full, clear, and exact description of the design, such as will enable others skilled in the art to which it appertains to 10 make and use the same, reference being had to the accompanying drawings, and to letters of reference marked thereon, which form a part of this specification.

Said drawing represents a corset in side elevation, showing the conformation of the hip portion, to which portion of a corset my design 15 relates.

The leading feature of the design consists in the outer surface of the hip portion of a 20 corset having the configuration hereinafter described.

A is said hip portion of a corset lying between the bust portion a' and back portion a'' . b is a midstripe or collection of stripes running vertically on the surface, which stripes 25 are ribbed corrugations. c are corrugated blocks lying laterally adjacent to the midstripe, the stripes in said blocks running approximately parallel to the midstripe. d are blocks of transverse stripes lying above the 30 vertical stripes c .

What I claim is—

The design for a corset, as herein set forth and shown.

In testimony that I claim the foregoing I 35 have hereunto set my hand this 29th day of September, 1883.

JAMES BOWERS.
